Patented Sept. 10, 1974

232,780

TEAT DILATOR FOR COWS

Eli A. Zackheim, Norwich, Conn., assignor to
Jules Silver, Norwich, Conn.

Filed July 7, 1972, Ser. No. 269,613

Term of patent 14 years

Int. Cl. D24—02

U.S. Cl. D83—12 R

FIG. 1

FIG. 2

FIG. 3

FIG. 4

FIG. 1 is a perspective front and side view of a teat dilator for cows showing my new design;

FIG. 2 is a front view of the teat dilator;

FIG. 3 is a side view of the teat dilator; and

FIG. 4 is a top plan view of the teat dilator.

I claim:

The ornamental design for a teat dilator for cows, substantially as shown.
